ANTENNA BASE

Edward Finkel, New York, N.Y., assignor to JFD
Electronics Corporation, Brooklyn, N.Y.

Filed Oct. 28, 1970, Ser. No. 22,929

Term of patent 14 years

Int. Cl. D14—03

U.S. Cl. D26—14

FIG. 1.

FIG. 2.

FIG. 3.

FIG. 4.

FIG. 5.

FIG. 6.

FIG. 1 is a front perspective view of an antenna base showing my new design;

FIG. 2 is a front elevation thereof;

FIG. 3 is a side elevation thereof;

FIG. 4 is a top plan view of a second modified embodiment of the antenna base illustrated in FIG. 1; and

FIG. 5 is a top plan view of a third modified embodiment of the antenna base illustrated in FIG. 1;

FIG. 6 is a top plan view of a fourth modified embodiment of the antenna base illustrated in FIG. 1.

The undisclosed rear portions of all the embodiments are unornamented.

I claim:

The ornamental design for antenna base, as shown and described.
